UNITED STATES PATENT OFFICE.

CLAUD L. PATTERSON, OF GOODING, IDAHO.

ADVERTISING FOLDER.

Application filed October 13, 1923. Serial No. 668,375.

This invention relates to an advertising folder particularly adapted for use in political campaigns. The folder is designed to reduce the cost of advertising literature, and at the same time to supply the public with more information concerning the candidates than has heretofore been possible to supply in a limited space. The invention consists of a folder card upon one of the leaves of which is secured one or more booklets containing interesting information regarding the candidates running for office. Such information, in addition, could include the picture of the candidate, and the office for which he is running. Thus in the State and county election one of the booklets will contain data on the county candidates and the other on the State candidates. The other leaf of the folder may contain the platform of the party that the candidates represent.

The above and other features of the invention will appear from the detailed description and accompanying drawing forming part of this specification.

In the drawing, Figure 1 is a plan view of the improved folder opened out, and

Figure 2 shows the folder closed in position for distribution or mailing.

For the convenience of description, the folder may be conveniently referred to as the upper section 1, and lower section 2. At one corner of the upper section 1 is a booklet 3 containing the desired data of the candidates for election. The other corner may also be provided with a similar booklet 4, but devoted to data concerning candidates on the same ticket but for different offices. Thus booklet 3 may be devoted to county candidates, and booklet 4, to State candidates.

The space between the booklets may be devoted to any suitable or desired writing concerning the candidates, either individually or collectively.

The lower part 2 of the improved folder is preferably given over to the statement of the platform of the party or some such other information as may be found desirable. The improved folder is particularly adapted for use in political campaigns, but it is susceptible of use in other ways. When used in political campaigns, the cost of distributing the literature concerning the candidates in the party is very materially reduced, and the information so given is kept in a convenient and more or less permanent form. The folder closed as shown in Figure 2 preserves the printing from soiling and the booklet from wear and tear. Any suitable means such as a paster 6 may be employed for sealing the folder for purposes of distribution or mailing.

The invention is comparatively simple, and has been found to be very practical for the purpose intended.

What I claim is:—

An advertising folder for use in political campaigns comprising a card folded book-fashion to form upper and lower leaves, a pair of booklets each secured to the inner face of the upper edge portion of the upper leaf of the card adjacent the respective upper corners of the same whereby the pages of each booklet are adapted to be turned upwardly on axes parallel to the fold line of the card without concealing any portion but a part of the upper edge of the upper leaf of the card, the booklets being spaced apart and each containing the picture and other data relative to a candidate, the upper card having a delineated space between the booklets to receive data regarding the candidates, and the inner surface of the lower leaf having a delineated space to contain the party platform.

In testimony whereof I affix my signature.

CLAUD L. PATTERSON.
